CLAIM

The ornamental design for an accessory storage device as shown and described.

DESCRIPTION

FIG. 1 is a rear perspective view of an accessory storage device according to an embodiment.

FIG. 2 is a front perspective view of the accessory storage device of FIG. 1.

FIG. 3 is a front view of the accessory storage device of FIG. 1.

FIG. 4 is a rear view of the accessory storage device of FIG. 1.

FIG. 5 is a left side view of the accessory storage device of FIG. 1.

FIG. 6 is a right side view of the accessory storage device of FIG. 1.

FIG. 7 is a top view of the accessory storage device of FIG. 1.

FIG. 8 is a bottom view of the accessory storage device of FIG. 1.

FIG. 9 is a rear perspective view of an accessory storage device according to another embodiment.

FIG. 10 is a front perspective view of the accessory storage device of FIG. 9.

FIG. 11 is a front view of the accessory storage device of FIG. 9.

FIG. 12 is a rear view of the accessory storage device of FIG. 9.

FIG. 13 is a left side view of the accessory storage device of FIG. 9.

FIG. 14 is a right side view of the accessory storage device of FIG. 9.

FIG. 15 is a top view of the accessory storage device of FIG. 9; and,

FIG. 16 is a bottom view of the accessory storage device of FIG. 9.

Portions of the accessory storage device shown in broken lines form no part of the claimed design.

1 Claim, 10 Drawing Sheets
